UNITED STATES PATENT OFFICE.

HERBERT ABRAHAM, OF NEW YORK, N. Y., ASSIGNOR TO THE RUBEROID COMPANY,
A CORPORATION OF NEW JERSEY.

SHINGLE MACHINE.

Application filed February 19, 1921. Serial No. 446,419.

To all whom it may concern:

Be it known that I, HERBERT ABRAHAM, a citizen of the United States, residing at the city, county, and State of New York, have 5 invented certain new and useful Improvements in Shingle Machines, of which the following is a specification.

The invention relates to a machine for cutting shingle strips from a web of prepared 10 roofing material.

Shingle strips consist of a plurality of units, generally two or four, forming integral flat strips, such for example as disclosed in my Patent No. 1,326,899, of January 6, 1920, which when laid in overlapping courses simulate the appearance of individual shingles.

According to my invention I provide a machine having a pair of rollers extending 20 transversely of the web and between which the web passes, each roller carrying cutting-dies so arranged that the dies carried on either roller operate against surface portions of the other roller as cutting beds, and 25 whereby at each revolution of the rollers completed shingle strips of the desired dimensions and shape, and having cleanly cut edges, are cut lengthwise from the continuously moving web.

30 The invention consists in the novel arrangement of parts hereinafter described and illustrated in the accompanying drawings, in which,

Figure 1, is a front view of the cutting 35 rollers of my improved machine, and,

Fig. 2, is a view of one of the completed shingle strips formed by said rollers.

The machine has a pair of rollers 1 and 2, mounted one above the other and between 40 which the material to be operated upon passes. Each roller is formed with a series of enlarged zones 3 and intervening zones 4 so arranged that the zones 3 of either roller are positioned opposite to the zones 4 of the other roller whereby to serve as beds against which the cutting-dies, carried on the portions 4, operate.

Suitably secured to the portions 4 of the 50 upper roller 1 are a series of cutting-dies 5 which extend circumferentially of the roller and are so designed as to form the longitudinal edges of the strips. Similarly the portions 4 of the lower roller 2 are provided with straight edge knives or dies 6 which

extend in the direction of the axis of the 55 roller and which form the ends or sides of the strips, said dies 6 being so positioned with relation to the dies 5 as to produce strips of the desired lengths.

If desired the roller 1 may be provided, in 60 addition to the cutting-dies 5, with suitable dies 7 for the purpose of forming slots or kerfs in one of the edges of the strip as shown.

The two rollers are geared together at 65 8 to rotate in unison and they are held in proper alignment with each other by means of the collars or flanges 9 disposed at the ends of the roller 1 and engaging the ends of the roller 2, or by any other suitable 70 means.

The machine is designed to operate upon a continuously moving web of prepared roofing material of the character usually employed in manufacturing shingles or strips, 75 and to cut said web, both longitudinally and transversely, into completed shingle strips at each revolution of the rollers. The enlarged portions 3 of each roller which intervene the cutting-dies carried on said rollers not only 80 serve as beds for the cutting-dies of the other roller to operate upon but also assist in producing cleanly cut edges because of the fact that they tend to slightly separate the strips, in the direction of the width of 85 the web, while the strips are being cut.

In Figure 2 of the drawings I have illustrated a completed shingle strip of the type formed by the cutting rollers shown in Figure 1. By referring to these figures it will 90 be seen that at each revolution of the rollers a plurality of such strips will be cut across the width of the web, and that the cutting-dies 5 will form the edges *a* of the strips, the cutting-dies 6 will form the ends *b*, and the 95 dies 7 will cut or punch out the slots or kerfs *c*.

Various modifications in the details of construction herein described and illustrated may be made without departing from the 100 scope of my invention.

What I claim is:

1. In a shingle machine, a pair of rolls each having alternating zones of different diameters respectively, each roll carrying 105 cutting-dies circumferentially of the zones of lesser diameter, the rolls being arranged with the zones of greater diameter of one in

alinement with the zones of lesser diameter of the other.

2. In a shingle machine, a pair of rolls each having alternating zones of different diameters respectively, each roll carrying cutting-dies circumferentially of the zones of lesser diameter, the rolls being arranged

with the zones of greater diameter of one in alinement with the zones of lesser diameter of the other, one of the rolls having flanges 10 at its end fitting over the ends of the other roll to keep the two in alinement.

HERBERT ABRAHAM.
